DESIGN FOR A COMBINATION DOUBLE SALAD FORK

Joseph L. Tonelli, Los Angeles, Calif., assignor of one-half to Michael E. Neish, San Leandro, Calif.

Application October 24, 1940, Serial No. 96,057

Term of patent 14 years

To all whom it may concern:

Be it known that I, Joseph L. Tonelli, a citizen of the United States and a resident of the city of Los Angeles, in the county of Los Angeles and State of California, have invented a new, original, and ornamental Design for a Combination Double Salad Fork, of which the following is a specification, reference being had to the accompanying drawing, forming part thereof.

Figure 1 is a top plan view of a combination double salad fork embodying my new design;

bination double salad fork.

I claim:

The ornamental design for a combination double salad fork, substantially as shown.

JOSEPH L. TONELLI.
